RAISED METAL PLAQUE

Filed Jan. 20, 1931

FIG. 1.

FIG. 2.

INVENTOR

CHARLES M. BECKER
BY *Hammond* ATTORNEY

UNITED STATES PATENT OFFICE

CHARLES M. BECKER, OF BROOKLYN, NEW YORK

DESIGN FOR A RAISED METAL PLAQUE

Application filed January 20, 1931. Serial No. 38,402. Term of patent 3½ years.

To all whom it may concern:

Be it known that I, CHARLES M. BECKER, a citizen of the United States, and a resident of the borough of Brooklyn, Kings County, city and State of New York, have invented a new, original, and ornamental Design for a Raised Metal Plaque, of which the following is a specification, reference being had to the accompanying drawings, forming a part hereof.

Referring to the annexed sheet of drawings:

Figure 1 is a front view of a plaque showing my new design.

Figure 2 is a cross-section substantially on the line 2—2 of Figure 1 showing the raised contour of the deer and the frame.

The plaque is a raised cast picture of deer in relief on a flat rolled metal background with certain ornamentation also in relief, such plaque being mounted in a beveled black wood frame giving a contrasting effect or finish of a raised picture.

I claim:

The ornamental design for a raised metal plaque as shown and described.

CHARLES M. BECKER.
